DRILL PRESS

Filed Sept. 11, 1944

Robert McFall Jones

By Robert M. Dunning

Attorney

10 from the spindle 14 so that the weight of the spindle is substantially counter-balanced.

As previously stated all of the foregoing construction is merely illustrative of a typical drill press construction which may be mounted on the standard 10.

The base 26 may be of any desired shape including a table portion 27 which extends beneath the spindle 14 and a table extension portion 29 which extends beneath the axis of the standard 10. The base 26 is preferably hollow and the table 27 thereof is provided with radially extending slots 30 emanating from the center of the table so as to provide a means by which work may be bolted to the table 27 or guides may be mounted thereon for properly positioning work with respect to the spindle. An elongated slot 31 is also preferably provided in the center of the table into which the drill 16 may extend when the drill passes through the object upon the table.

An arm 32 is secured to the base 26 by any suitable means such as by bolts 33. The arm 32 extends upwardly from the rear end 34 of the base 26 and then extends substantially parallel to the base and spaced substantially above the same. The extreme end of the arm 32 is provided with vertically aligned apertures 35 of a size to accommodate the standard 10. A set screw 36 extends into the arm end 37 for holding the standard 10 in set relation to the arm 32. This set screw 36 may be tightened when the standard 10 is in the elevated position illustrated in Figure 1 of the drawings, leaving the upper surface of the table 26 entirely free from the front edge thereof to the arm 32. Alternatively the set screw 36 may be tightened while the standard 10 is in lowered position, as in Figure 2 of the drawings.

A socket 38 is provided in the base 26 in axial alignment with the apertures 35. Thus when the standard 10 is in the lowered position illustrated in Figure 2 of the drawings the standard 10 may be engaged in the socket 39 and be braced by the arm 32 which engages the standard at a point spaced from the lower extremity thereof. Thus in lowered position the standard is support-

ed even more securely than in conventional equipment, while in raised position the support is as firm as with usual construction.

It should be noted that when the standard is in the elevated position shown in Figure 10 of the drawings, work of relatively large perimeter may be drilled, portions of this work extending between the arm 32 and the upper surface of the base table 26. Much larger work may thus be handled by the drill press without lengthening the spindle supporting arm 11 or increasing the eccentric load upon the standard 10.

In accordance with the patent statutes, I have described the principles of construction and operation of my drill press, and while I have endeavored to set forth the best embodiment thereof, I desire to have it understood that obvious changes may be made within the scope of the following claim without departing from the spirit of my invention.

I claim:

A drill press comprising a base, an arm having one end secured to said base to extend upwardly therefrom, said arm having a free end extending laterally to position the free end laterally spaced from the end thereof connected to said base, a standard adjustably secured to said free end of said arm, a spindle support extending laterally from said standard, and a socket in said base of a diameter to receive the lower end of said standard in one adjusted position thereof and to hold said standard from lateral movement.

ROBERT McFALL JONES.
